Primary Examiner—Martie K. Holtje(74) *Attorney, Agent, or Firm*—Gifford, Krass, Groh, Sprinkle, Anderson & Citkowski, P.C.(57) **CLAIM**

The ornamental design for desktop container, as shown and described.

DESCRIPTION

FIG. 1 is a perspective view of an embodiment of a desktop container with the lid closed; and,

FIG. 2 is a perspective view of the desktop container of FIG. 1 with the lid removed so as to show items stored therein, the portions shown in broken lines are shown for illustrative purposes only and form no part of the claimed design.
